[57] CLAIM

The ornamental design for a case for tape cartridges and cassettes, as shown and described.

DESCRIPTION

FIG. 1 is a perspective view of a case for tape cartridges and cassettes showing my new design with cover in an open position, the interior surfaces of the opposed side walls being identical;

FIG. 2 is a right side elevational view thereof in a closed position;

FIG. 3 is a top plan view thereof;

FIG. 4 is a front elevational view thereof; and,

FIG. 5 is a rear elevational view thereof.

FIG. 1

FIG. 2

FIG. 3

FIG. 4

FIG. 5
